FEELER MOVING MECHANISM

Albert A. Gordon, Worcester, Mass., assignor to
Crompton & Knowles Loom Works, Worcester,
Mass., a corporation of Massachusetts

Application August 1, 1933, Serial No. 683,144

4 Claims. (Cl. 139—233)

This invention relates to automatic looms in which a weft detector or feeler is associated with a set of vertically moving shuttle boxes at one side of the loom.

5 It is the general object of my invention to provide improved pattern controlled means for moving the feeler vertically and for locking the feeler-moving means in a selected position after operation thereof.

10 In the preferred form, this feeler-moving means is actuated from the dobby pattern chain through special indicating levers associated with the usual vibrator levers.

15 My invention further relates to arrangements and combinations of parts which will be herein-after described and more particularly pointed out in the appended claims.

A preferred form of the invention is shown in the drawings, in which

20 Fig. 1 is a front elevation of a loom embodying my improvement;

Fig. 2 is a partial side elevation, looking in the direction of the arrow 2 in Fig. 1 and showing certain parts in section;

25 Fig. 3 is an enlarged front elevation, partly in section, of a dobby and parts of the feeler-moving mechanism;

Fig. 4 is a detail plan view, looking in the direction of the arrow 4 in Fig. 3;

30 Fig. 5 is a detail sectional elevation, taken along the line 5—5 in Fig. 3;

Fig. 6 is an enlarged front elevation of certain feeler and drop box positioning mechanism, looking in the direction of the arrow 6 in Fig. 2;

35 Fig. 7 is a side elevation of the parts shown in Fig. 6, with a part of the cover plate removed;

Fig. 8 is a detail sectional view, taken along the line 8—8 in Fig. 6, and

40 Fig. 9 is a detail sectional view, taken along the line 9—9 in Fig. 7.

Referring to Fig. 1, I have shown a loom having the usual loom frame 10 and top girt 11, magazine 12, drop boxes 13 and 14 mounted at opposite ends of the lay 15, harnesses 16, and a dobby

45 17 by which the movements of the drop boxes and harnesses are controlled. The dobby 17 is provided with the usual vibrator levers 18, vibrator gears 19 and upper and lower cylinder gears 20 and 21, also with the usual lock knife 22 and

50 with the usual mechanism (not shown) for withdrawing the lock knife during the shifting of the vibrator levers.

A feeler-moving lever 29 is mounted on the loom frame 10 at the detecting side of the loom

55 and the rear end of the lever 29 is connected by a link 32 (Fig. 2), a short chain 33 (Fig. 1) and a link 34 to a bent lever 35 (Fig. 3) mounted on a pivot stud 36 in a fixed bracket 37. The upper end of the lever 35 is segmental in shape and is

60 provided with a plurality of notches 38 to receive

a V-shaped lug 39 on a locking lever 40 swinging about a fixed pivot 41. The lever 40 is yieldingly pressed downward by a spring 42.

The locking lever 40 is connected by a link 44 to the offset outer end 45 of a special indicating lever 46 mounted on the cross rod 47 which supports the usual vibrator levers 18. The lever 46 has a contact plate 48 positioned for engagement by rolls 49 on a pattern chain 50 mounted on the usual intermittently operated pattern cylinder 53. A roll is provided under the plate 48 for each cross bar of the chain 50, so that the lever 46 is raised and the locking lever 40 is lifted from the notched segment of the lever 35 at each advance movement of the cylinder 53 and pattern chain 50.

A pair of vibrator levers 18^a and 18^b (Fig. 4) have their outer ends pivotally connected at 62 and 63 respectively to the opposite ends of a floating lever 64. A link 65 connects an intermediate point 66 on the floating lever 64 to a stud 67 on the bent lever 35. By raising or lowering one or both of the vibrator levers 18^a and 18^b, four different positions of the bent lever 35 may be determined, with four corresponding vertical positions of the feeler moving lever 29.

It will be noted that the contact plate 48 for the lever 46 which controls the locking lever 40 is engaged by the rolls 49 of the pattern chain somewhat earlier than the contact plates 70 of the vibrator levers 18. By thus advancing the contact plate 48, the locking lever is lifted prior to swinging movement of the bent lever 35 occasioned by the action of the vibrator levers 18^a and 18^b.

The mechanism for moving and positioning the drop boxes 14 and for connecting the feeler 25 to the feeler-moving lever 29 are of the general type shown in the prior patent to Nelson, No. 1,674,871, issued June 26, 1928. The details of the mechanism and connections are shown in Figs. 6, 7 and 8 and will now be briefly described.

The drop boxes 14 (Fig. 2) are mounted on the usual lifter rod 75 which is vertically slidable in a bearing member 76 mounted on the lower rock shaft 77. A lifting member 78 vertically positions the lifter rod 75 and the drop boxes 14, and the member 78 is shifted vertically by the usual box shifting mechanism (not shown).

The lifting member 78 has a forwardly projecting portion 79 to which is secured the lower end of a rack bar 80. The rack bar 80 is slidable vertically in guideways in a casing 81 (Fig. 7) fixed to the loom side 10. The teeth of the rack bar 80 engage a pinion 82 rotatable on a stud 83 fixed in the casing 81.

The pinion 82 also engages the teeth of a second rack bar 84, also slidable vertically in guideways in the casing 81.

A second pinion 85 is mounted on a stud 86

(Fig. 9) fixed in a plate 87 vertically slidable in guideways on the outside of the casing 81. A stud 86^a (Fig. 8) is connected at one end to the plate 87 as at 87^a and the other end is connected by a link 88 (Fig. 2) to a stud 89 adjustably secured in the forward end of the feeler-moving lever 29 previously described.

A third rack bar 90 (Fig. 7) is slidable in guideways in the casing 81 and is engaged by the teeth of the pinion 85 which is mounted on the slide plate 87. It will be noted by reference to Fig. 9 that the rack bar 84 is of greater width, so that it engages the teeth of both pinions 82 and 85, while the rack bar 80 engages the pinion 82 only and the rack bar 90 engages the pinion 85 only.

A bracket 91 is secured to the upper end of the rack bar 90 and forms a support for the weft detector or feeler 25.

While the arrangements of parts is somewhat different from that shown in the Nelson patent above identified, the method of operation is substantially the same as in the patent and is as follows:

It has been previously explained that on a box change the feeler-moving lever 29 will be operated earlier than the drop box lifting member 78. Or, in other words, the lifting member 78 will be at rest during the feeler-adjusting movement of the lever 29.

30 The lever 29 is directly connected by the link 88 to the slide plate 87 and the slide 87 carries the pinion 85. Consequently, any swinging movement of the lever 29 will cause a corresponding vertical adjustment of the pinion 85.

35 The pinion 85 on the slide plate 87 simultaneously engages the rack bars 84 and 90, as previously explained, and the pinion 82 fixed in the casing 81 simultaneously engages the rack bars 80 and 84.

40 The rack bar 80 is connected to the lifting member 78 which remains fixed during movement of the lever 29. Consequently the rack bar 80 is held stationary and in turn holds the pinion 82 from rotation. Consequently the rack bar 84 is also stationary but the rack bar 90 is free to move.

45 Under these conditions, vertical movement of the pinion 85 by the lever 29 will cause the pinion 85 to roll on the temporarily fixed rack bar 84 and will thus give the rack bar 90 and feeler 25 a vertical movement equal to twice the vertical movement of the pinion 85. The feeler 25 is thus moved promptly to a position in vertical alignment with the drop box about to be placed in running position.

50 The lever 29 is then secured from displacement by the rocking member 40 previously described, and consequently the pinion 85 remains in fixed vertical position during the ensuing box change.

60 As the lifting member 78 is thereafter moved vertically to shift the drop boxes, the rack bar 80 will be directly moved vertically, causing rotation of the pinion 82 mounted on the fixed pivot 83. Such rotation of the pinion 82 will cause a movement of the rack bar 84 in the opposite direction to that of the movement of the rack bar 80 but of equal extent.

65 As the rack bar 84 engages both pinions 82 and 85, this movement of the rack bar 84 will cause the pinion 85 to rotate simultaneously with and in the same direction as the pinion 82. Consequently the rack bar 90 will be adjusted vertically in the same direction as the rack bar 80 and to

the same extent, thus keeping the feeler 25 aligned with the selected drop box during the vertical movement of the selected box to running position.

For a more complete description of the construction and operation of the feeler adjusting mechanism, reference is made to the Nelson patent above identified. 5

I have thus provided improved means for initially positioning the weft detector or feeler, which positioning means is directly under the control of 10 the dobby pattern chain, and I have also provided means for securely locking the feeler in adjusted relation to the drop boxes during the subsequent shifting of the boxes, the indicating lever 46 being locked in lowered position by the lock 15 knife 22 during such shifting movement.

Having thus described my invention and the advantages thereof, I do not wish to be limited to the details herein disclosed, otherwise than as set forth in the claims, but what I claim is:— 20

1. In a loom, a plurality of shifting shuttle boxes, means to shift said boxes, a feeler, a dobby, a pair of dobby levers, a pattern chain for moving said levers, and actuating connections from said levers to said feeler through which said feeler is vertically adjusted with respect to the drop boxes by said dobby levers in accordance with the indications of said pattern chain, said actuating connections including a positioning lever having a 25 notched segmental portion, a latch and means to move said latch into engagement with one of said notches to lock said lever from movement after selected adjustment of said lever and feeler.

2. In a loom, a plurality of shifting shuttle boxes, means to shift said boxes, a feeler, a dobby, a pair of dobby levers, a pattern chain for moving said levers, and actuating connections from said levers to said feeler through which said feeler is vertically adjusted with respect to the drop boxes by said levers in accordance with the indications of said pattern chain and in advance of the corresponding movement of the drop boxes, said actuating connections including a positioning lever mounted on a fixed pivot, a floating lever pivoted at its ends to the ends of said dobby levers, 35 and a link pivoted at its ends to said positioning and floating levers respectively, whereby said positioning lever is selectively and jointly located by said two dobby levers.

3. In a loom, a plurality of shifting shuttle boxes, means to shift said boxes, a feeler, a dobby, a pair of dobby levers, a pattern chain for moving said levers, actuating connections from said levers to said feeler through which said feeler is vertically adjusted with respect to the drop boxes by said levers in accordance with the indications of said pattern chain, and means in said actuating connections to lock said feeler in a selected position after adjustment of the feeler. 50

4. In a loom, a plurality of shifting shuttle boxes, means to shift said boxes, a feeler, a dobby, a pair of dobby levers, a pattern chain for moving said levers, actuating connections from said levers to said feeler through which said feeler is vertically adjusted with respect to the drop boxes by said levers in accordance with the indications of said pattern chain, and means to lock said actuating connections in a selected position after adjustment of said feeler, said locking means being controlled by an additional dobby lever. 60

ALBERT A. GORDON.
